United States Patent Office.

MARTIN J. MELLYN, OF ROXBURY, MASSACHUSETTS.

Letters Patent No. 69,689, dated October 8, 1867.

IMPROVED CUTTING-TOOL.

The Schedule referred to in these Letters Patent and making part of the same.

TO ALL WHOM IT MAY CONCERN:

Be it known that I, MARTIN J. MELLYN, of Roxbury, in the county of Norfolk, and State of Massachusetts, have invented a new and improved Cutting-Bar; and I do hereby declare that the following is a full, clear, and exact description thereof, which will enable those skilled in the art to make and use the same, reference being had to the accompanying drawings, forming part of this specification.

This invention relates to a new and improved device for cutting off the projecting ends of bolts which are used for fastening tires on to wagon-wheels; and the invention consists in a bar of peculiar form, which is made to support and guide a chisel, and which also forms an anvil against or on which the cutting is done, as will be hereinafter described.

Figure 1 represents a longitudinal side view of the machine, showing the bar and the chisel, and the manner of its application.

Figure 2 is a longitudinal view of the same from the back side.

Figure 3 is a cross-section of the bar at the line *xx*.

Similar letters of reference indicate corresponding parts.

A represents the bar. B is the chisel. The bar is formed with a shoulder, C, which is an anvil for the cutting-chisel. The portion of the bar which rises from the anvil is marked D. At its upper end there is a socket or staple, E, through which the chisel passes, and by which it is held in place. At the lower or opposite end of the bar there is a claw, F, for removing bolts when necessary.

A difficulty has always been experienced in cutting off the ends of the bolts which protrude through the nuts after the tire has been fastened to the wheel. All devices for this purpose which have been heretofore resorted to have left a portion of the bolt to be filed off, making it a tedious and expensive operation. By the use of my machine the bolt is cut clean with the nut, (or nearly so,) requiring but a slight touch of the file afterwards.

This apparatus is also used to great advantage in splitting nuts, and thus removing them in cases where the bolt turns round in the tire and felloe of the wheel. In ordinary practice it is difficult either to split the nut or cut off the bolt without marring the paint and injuring the wheel, but with this bar and chisel it is an easy matter. In both cases the bar is held in the hand, with the anvil C against the nut, when a hammer is used upon the chisel, the wheel being in a horizontal position on a bench or stand for the purpose.

Having thus described my invention, I claim as new, and desire to secure by Letters Patent—

The bar A, constructed substantially as shown and described, with the anvil C and socket E, in combination with the chisel B, substantially as and for the purposes herein set forth and described.
